UNITED STATES PATENT OFFICE.

BRUNO MEYER, OF BERLIN-CHARLOTTENBURG, GERMANY, ASSIGNOR TO THE FIRM
JULIUS PINTSCH AKTIENGESELLSCHAFT, OF BERLIN, GERMANY.

DIRECT-COMBUSTION GRATE-BURNING PROCESS WITH SEPARATE DISTILLATION AND COMBUSTION OF THE FUEL.

Application filed March 21, 1921. Serial No. 454,130.

(GRANTED UNDER THE PROVISIONS OF THE ACT OF MARCH 3, 1921, 41 STAT. L., 1313.)

To all whom it may concern:

Be it known that I, BRUNO MEYER, a citizen of the Republic of Germany, residing at Berlin-Charlottenburg, Germany, have invented a new and useful Direct-Combustion Grate-Burning Process with Separate Distillation and Combustion of the Fuel (for which I have filed application in Germany, December 11, 1917, Patent No. 339,729, August 6, 1921), of which the following is a specification.

That the burning of coal is attended with a great waste of its constituent parts the conservation of which would be a great public benefit is a fact that is becoming more and more widely known. The first attempts in this direction led to the recovery of the by-products by the distillation of the coal in gas generators and the subsequent burning 20 of the gas beneath the boilers. But this process is expensive because on the one hand a considerable amount of heat is lost which has to be made up for by an additional coal consumption and on the other hand the construction and working of the gas generating 25 plant involve considerable expenditure that is seldom covered by the profit derived from the by-products.

But vastly improved conditions will be obtained if the coal is treated according to the novel process hereinafter described. An application of this process is illustrated in the drawing which represents a longitudinal section of a boiler with a travelling grate. 30 Hitherto the coal was fed from the coal bunker *a* onto the travelling grate *b* where it was burnt to ashes. According to the present invention a distillation shaft or trunk *c* is interposed between *a* and *b* and 35 connected by a pipe *d* with a by-product recovery plant *e* and a gas exhauster *f* by which a small portion of the gases of combustion formed on the grate *b* is drawn through the shaft *c* and the plant *e*. By 40 this means tar, ammoniac etc. is recovered and separated whilst the residual permanent gases of this mixture of gases of combustion and distillation are sent back by the exhauster *f* to the combustion chamber of the 45 boiler where they issue from the burner *g* or at any other part of the furnace.

To separate the volatile components con-

tained in the coal it is not by any means necessary to draw the whole of the gases obtained by combustion through the feed shaft *c*, a comparatively small amount of these gases being sufficient for this purpose and a large proportion of the same being reduced to carbon monoxide and hydrogen in the bottom end of the shaft *c* by the action of the incandescent carbon that will be present there. This gas mixture mixes in the upper part of the shaft *c* with gases of distillation and passes out of the shaft at a low temperature without the valuable constituents (tar and ammonia) being destroyed, which very often happens in distillation shafts that are heated from the exterior.

It follows from the preceding paragraphs that the invention contemplates a direct 70 grate-combustion in which with the aid of corresponding quantities of air, the entire fuel is completely burnt to carbon dioxide and steam; i. e., the new process differs entirely from the process that takes place above 75 the grate of a gas generator inasmuch as the process of distilling the fuel in the generator is done away with.

A clear distinction has so far been made between the two processes—viz, the production of gas in generators and the two principal distillation processes in the manufacture of coke and lighting-gas—which have hitherto enabled the valuable by-products of coal to be recovered, and the direct combustion of 80 coal on furnace grates, which does not permit of the utilization of the by-products, because the object of the invention is to entirely change this state of things by providing 85 means by which a recovery of the valuable by-products of coal, especially of the low-temperature-tar that is now so frequently mentioned, can be successfully carried out in connection with ordinary grate fires even in the smallest plants, as for instance in connection with steam boilers.

The principal advantages of the new process as compared to the only processes that have hitherto been employed for recovering the by-products of coal, viz, gas production 100 by generators and the two distillation processes used in producing coke and lighting-gas consist in the following two points:

1. In the direct burning of coke that has

been produced in coke ovens or gas retorts considerable amounts of heat are wasted through the coke thus produced having to be cooled off, whereas the heat that is taken up by the coke formed in the distillation shaft in accordance with the present invention is restored by it to the furnace.

2. In the case of gas furnaces the losses of heat in the gas producer are added to the loss in the furnace so that the former give rise to an increase of the fuel consumed. Besides the working of gas producers is generally more troublesome and dearer because to reduce the carbon dioxide and steam the layer of fuel has to be kept even and to accomplish this considerable care has to be taken to prevent hollow spaces being formed by the slags, which is out of the question in the direct combustion process in which the coal is burnt in thin layers. Another point is that in working with gas producers a large amount of steam must generally be used to prevent the formation of slags. Hence it is also necessary to conduct a larger quantity of the gases formed in the gas producing chamber through the distillation chamber so as to maintain in this latter the temperature required for gas formation. This involves the cooling and cleaning of larger quantities of gas than in the process according to the invention, which entails an increase of the costs of the recovery of the by-products.

I claim:

35 1. A direct combustion grate-burning process with separate distillation and com-

bustion of the fuel consisting in feeding the fuel from a fuel supply through a distillation chamber and on to the grate of a furnace, conducting a sufficient amount of the 40 gases of combustion through said distillation chamber to maintain said chamber in the condition required for the formation of ammoniac and low temperature tar, conducting the products of distillation from the distillation chamber, cooling and cleaning the products of distillation for the purpose of separating the valuable by-products, and finally conducting the gases of distillation back to the combustion chamber of the furnace.

2. A direct combustion grate-burning process with separate distillation and combustion of the fuel consisting in feeding the fuel from a fuel supply through a distillation chamber and into a combustion chamber, passing a sufficient amount of the combustion gases from the combustion chamber through the distillation chamber to maintain the fuel in the distillation chamber at a temperature required for the formation of ammoniac and low temperature tar, withdrawing the products of distillation from the distillation chamber, cleaning and cooling the distillation products for the purpose of separating the valuable by-products from the distillation gases, and forcing the diluted gases into the combustion chamber and burning the same therein.

In testimony whereof I affix my signature.

BRUNO MEYER.
